UNITED STATES PATENT OFFICE

HARRY C. FOSTER, OF CONNERSVILLE, INDIANA, ASSIGNOR TO INDIANA LAMP CORPORATION, OF CONNERSVILLE, INDIANA, A CORPORATION

REFLECTOR FOR HEADLIGHTS

Application filed February 14, 1927. Serial No. 167,998.

This invention pertains to a reflector particularly adapted to be used in connection with vehicle headlights.

The main feature of the invention resides in the provision of a reflector formed of one piece of metal having its reflecting surface comprised of a plurality of parabolic sections, each of which is of a different focal length, said sections merging into each other so as to 5 avoid any substantial break between their adjoining surfaces, whereby the beams of light projected from each of said surfaces will form a combined pattern such as to comply with the present day requirements, as will 10 15 hereinafter be more fully set forth and described.

Another feature of the invention resides in the provision of vertical flutes or flats of varying widths in each of the reflecting surfaces for spreading the light rays projected therefrom and distributing the same in such fashion as to form a combined beam of the desired or required "spread", without the requirement of the usual diffusing spreading 20 25 lens of the prismatic character. Thus a headlight embodying this reflector may be employed with a plain clear glass lens or closure.

Still another feature of the invention resides in the provision on one of the reflecting surfaces, the lower one as herein shown, of a plurality of flat surfaces formed by combining horizontally-extending flats with the vertically-extending flats. This formation of the reflecting surface so disperses the rays projected therefrom as to reflect them over substantially the entire pattern, or the greater portion thereof so as to eliminate dark spots or shadows which may occur by reason of the merging of the light beams from the other sections, or defects in the commercial reflector.

A reflector having the above characteristics, and constructed as hereinafter more fully set forth and described will project a beam having the desired lateral spread cut-off at the top, and by reason of the relative angular displacement of the sections, will project the light below a horizontal plane through its axis, the central portion of the beam being of maximum intensity for projecting the

beam at the greatest distance down the road, the lower and lateral portions of the beam shading off toward the bottom and sides. Furthermore, by reason of this construction, a double filament bulb may be used in such fashion as to raise or lower the beam to the desired extent without noticeably affecting the light pattern produced thereby.

The full nature of the invention will be understood from the accompanying drawings 60 and the following description and claims.

In the drawings, Figure 1 is a front elevation of the reflector. Fig. 2 is a central vertical section therethrough. Fig. 3 is a sectional illustration of the formation of the reflecting surface of the upper section A adjacent its connection with section B. Fig. 4 is the same with respect to section B adjacent its connection with section C. Fig. 5 is a sectional illustration taken on a horizontal plane through the center of the reflector showing the formation of the reflecting surface of section C. Fig. 6 is the same as Figs. 3 and 4 with respect to section D adjacent its connection with section C. Fig. 7 is a diagrammatical illustration showing the light pattern or distribution of the rays. Fig. 8 is a diagrammatical illustration of the combined parabolic sections forming the reflector shown in Figs. 1 and 2.

In the drawings there is shown a reflector 10 having the usual annular flange 11 and opening 12 in the center thereof for a lamp bulb, said reflector being formed of a plurality of parabolic sections in a vertical plane 85 associated together, comprising the sections A, B, C and D.

The reflecting surface A is provided with a plurality of flats 13 and 14, as shown in Figs. 1 and 3. Said flats extend vertically when the reflector is properly mounted, there being one centrally-positioned flat 13 on each side of which there are flats 14 of a greater width. The reflecting surface B is provided with a plurality of vertically-extending flats 15 of substantially the same width throughout the entire section. Section C is formed of a plurality of vertical flats 16 and 17, the flats 16 being of less width than the flats 17. Section D is provided with a plurality of 100

vertical flats 18, 19, 20 and 21, increasing in width from the center toward each side. Said section D also has horizontally-extending flats of a uniform width, whereby the parabolic surface thereof is broken up into a plurality of substantially flat rectangular surfaces which will spread the beam projected thereby in a vertical plane as well as a horizontal plane.

- 10 Referring to Fig. 8 and considering the sections as intercepted by a vertical plane through the center of the reflector, section C comprises a parabola with a focal length less than D and greater than sections A and B as shown herein 1 and 5/16 of an inch, and having its axis indicated by the line X—X with its focal point at F^c, the projection of continuation of the curve being indicated by c—c.
- 15 Section B has a focal length of 1 and 3/16 of an inch as shown herein, which is less than sections C and D but greater than section A, its focal point F^b being positioned close, but slightly to the rear of the focal point F^c on its axis X—X. As shown it is divided from section C on the line indicated by Y—Y, and is positioned forwardly of section C .093 of an inch. Both sections B and C have the same axis X—X.
- 20 Section A has a focal length of 1 and 1/32 of an inch, which is less than any of the other sections, and it is positioned immediately above section B, having its focal point F^a lying on the line X—X to the rear of the focal point F^b. This section is tilted downwardly approximately three degrees so that its axis will extend downwardly with respect to the axis X—X as indicated by X^a—X^a.

Section D has a focal length of 1 and 3/8 of an inch, which is greater than that of the other sections. It is positioned at the bottom of the reflector below section C. Its focal point F^d is positioned on the line X—X slightly in front of the focal point F^c and it is tilted downwardly approximately one degree so that its axis extends on the line X^d—X^d.

In employing the reflector with a double filament bulb, the bulb is so positioned that the lower filament will lie approximately upon the axis X—X between the focal points F^a and F^d, while the upper filament will be positioned substantially on the line X'—X'. As shown in Fig. 7, a source of light positioned in the focal area of the reflector will produce a pattern on a vertical screen at about 25 feet, wherein the section A throws the lowermost pattern having the greater spread, as indicated by "sec. A" on said pattern, when the reflector is in horizontal position, extending from three to six degrees below horizontal and having a spread of about thirty-two degrees or sixteen degrees on each side of the center. This forms the lowermost and widest section of the beam due to the

three degrees downward inclination of the reflecting surface and the relatively wide vertical flats. The beam projected by section B, which will partially be superimposed upon the pattern of section A, extends from one to six degrees below horizontal and has a spread of about twenty-six degrees, or thirteen degrees on each side of the center. This is due to its horizontal position a distance above the center of the reflector with its focal point very slightly below the line X—X, sufficient to drop the beam about one degree, its spread of twenty-six degrees being caused by the flats 15.

The pattern projected by the principal or center section C is more concentrated, extending from horizontal to about three and one-half degrees below horizontal, having a maximum spread of about twenty degrees, ten degrees on each side of center, as illustrated in Fig. 7 by "sec. C". The greater intensity of light will be projected from this substantially central section C and the light will be spread over a smaller area than the spread from the other sections so as to be more concentrated, the smaller flats 16 at the center of the section causing the beam to spread laterally only to a slight extent, as shown herein about five and one-half degrees on each side of center, whereas the wide flats 17 extend or spread in a narrower form about four and one-half degrees further on each side of center. The lower or bottom section D distributes its beam over a much greater area than any of the other beams, from horizontal or zero to about six degrees below horizontal, having a lateral spread of only about nine degrees on each side off center, as indicated by "sec. D". This is the result of the flat surfaces caused by the combined vertically and horizontally extending flats which effect both a vertical and a horizontal spread. The rays coming from this lower section and overlapping all the other sections act to iron out any dark spots or shadows and smooth out the beam.

As the most desirable light should have its greatest intensity at about one and one-half degrees below horizontal so as to strike and illuminate the road more intensely at the proper distance from the vehicle, it will be noted in Fig. 7 that the rays from the three principal beams are superimposed in this area, thus effecting the desired intensity.

The invention claimed is:

1. In combination with a source of light, a reflector adapted to receive light rays therefrom and to reflect said light rays so as to form a light pattern upon an object placed in the path of said rays, said reflector having a plurality of reflecting sections substantially parabolic in general contour including a section having its axis inclined to direct its beam to a portion only of the light pattern and having a plurality of sub-sections substantially

flat in the horizontal direction formed across its surface for lateral diffusion of light, a second section having its axis inclined to direct its beam to a different portion of the 5 light pattern and having a plurality of wider sub-sections substantially flat in the horizontal direction formed across its surface for wider lateral light diffusion, and a third section having a plurality of sub-sections sub- 10 stantially flat in both vertical and horizontal directions for both vertical and lateral light diffusion and having its axis inclined to direct its beam over substantially the entire light pattern in the vertical direction whereby the 15 intersection of the beams of the first two sections is rendered unnoticeable.

2. In combination with a source of light, a reflector adapted to receive light rays therefrom and to reflect said light rays so as 20 to form a light pattern upon an object placed in the path of said rays, said reflector having a plurality of reflecting sections substantially parabolic in general contour including a section having its axis inclined to direct 25 the beam therefrom to the upper portion of the light pattern and having a plurality of sub-sections substantially flat in the horizontal direction formed across its surface for lateral diffusion of light, a second section hav- 30 ing its axis inclined to direct the beam therefrom to the lower portion of the light pattern and having a plurality of wider sub-sections substantially flat in the horizontal direction formed across its surface for lateral light 35 diffusion wider than said first section, and a third section having its axis inclined to direct the beam therefrom over substantially the entire light pattern in the vertical direction and having a plurality of sub-sections 40 substantially flat in both vertical and horizontal directions for both vertical and lateral light diffusion, whereby the beam from said last-mentioned section renders the intersection of the beams from said first-mentioned 45 sections unnoticeable.

3. In combination with a source of light, a reflector adapted to receive light rays therefrom and to reflect said light rays so as to form a light pattern upon an object placed 50 in the path of said rays, said reflector having a plurality of reflecting sections substantially parabolic in general contour including a section having its axis inclined to direct the beam therefrom to the upper portion of the light pattern and having a plurality of sub-sections substantially flat in the horizontal direction formed across its surface for lateral diffusion of light, a second section having its axis inclined to direct its 55 beam over substantially the entire light pattern in the vertical direction and having a plurality of wider sub-sections substantially flat in the horizontal direction formed in its surface for wider lateral light diffusion, a 60 third section having its axis inclined to direct 65

its beam to the lower portion of the light pattern and having a plurality of sub-sections substantially flat in horizontal direction formed in the surface thereof wider than those in the surface of said second-mentioned section for lateral light diffusion wider than said second-mentioned section, and a fourth section having its axis inclined to direct its beam over substantially the entire light pattern in the vertical direction 70 and having a plurality of sub-sections sub- 75 stantially flat in both horizontal and vertical directions for both horizontal and vertical light diffusion, whereby the intersection of the pattern of the first three sections is rendered unnoticeable.

In witness whereof, I have hereunto affixed my signature.

HARRY C. FOSTER.
